UNITED STATES PATENT OFFICE.

ROBERT FARNWORTH AND THOMAS TROUGHTON JACKSON, OF BOLTON, ENGLAND,
ASSIGNORS TO BONWEB, INCORPORATED, OF BOSTON, MASSACHUSETTS, A CORPO-
RATION OF MAINE.

SHUTTLE FOR WEAVING-LOOMS.

1,286,969.

Specification of Letters Patent. Patented Dec. 10, 1918.

Application filed September 28, 1912. Serial No. 722,965.

To all whom it may concern:

Be it known that we, ROBERT FARNWORTH and THOMAS TROUGHTON JACKSON, subjects of the King of Great Britain and Ireland, and residents of Bolton, in the county of Lancaster, England, cotton manufacturer and engineer, respectively, have invented certain new and useful Improvements in Shuttles for Weaving-Looms, of which the following is a specification.

Our invention has reference to improvements in shuttles for weaving looms and more particularly to such as are employed in small ware looms, or looms of the Poyser type, the object being to provide an improved form of shuttle body and improved tension and braking arrangements for the weft.

Our invention will be fully described with reference to the accompanying drawings in which—

Figure 1 is a front elevation of the improved shuttle,

Fig. 2 side elevation,

Fig. 3 plan and

Fig. 4 sectional side elevation.

Our invention consists in forming the shuttle body *a* from one piece of sheet metal, preferably steel, which is bent up at the ends *b* to form bearings *c* for holding the weft bobbin *d* while it is so shaped at the front corners *e* as to stroke down any slack warp threads that may protrude in the bottom of the warp shed and to stroke up by means of the inclined front edges *f* in a similar manner any slack ends in the upper portion of the warp shed.

A further feature is the arrangement of the tension lever *g* which is pivoted at *h* and is of hooked formation at one end *i* the opposite end being formed into an arm *j* adapted to come in contact with the loom stopping mechanism when the weft breaks. To pull the hooked end *i* of the tension lever toward the bobbin *d* against the tension of the weft an elastic member is employed. This may consist of an elastic band *k* in the form of a loop one end being hooked on to the lever and the other to the bent end *m* of wire pivot rod *m*, carried in bearings *m* struck up from the body of the shuttle. Pivoted on said rod *m* is the spring-controlled braking plate *n* for preventing overrunning of the weft bobbin *d*. *o* is the con-

trolling spring, of which one end bears 55 against the braking plate *n*, so that the plate is held yieldingly in engagement with the bobbin. The weft *p* is passed around the hook *i* of the tension lever *g* in a novel way which is facilitated by an improved construction of the nose *q* of the shuttle. This nose is bent up and is formed with a slot *s* and with a rearwardly curved cross bar or loop *r*. The tension lever is so pivoted that the hook *i* thereof may be swung forwardly 60 through the slot *s* past the loop *r*, whereupon the weft can be simply passed on to the hook *i*. When the tension lever is drawn back by the elastic band, a loop of the weft is drawn around the loop *r* of the shuttle nose, and 65 the weft then emerges from the slot as shown by the direction of the weft in Fig. 3. Should the weft break the elastic band *k* pulls the hooked end *i* of the tension lever toward the weft bobbin *d* and brings the 70 arm *j* at the other end into position for stopping the loom. A projection *t* is employed to prevent the tension lever turning 75 too far.

One of the bearings *c* is circular while the 80 other is openly-slotted so that the bobbin *d* can be readily interchanged.

The arm *j* may be adapted to operate any suitable form of loom stop mechanism which does not, however, constitute any part of 85 our present invention.

The improved shuttle is simple and cheap to construct and is very effective for the purpose for which it is intended.

What we claim as our invention and desire to secure by Letters Patent is:—

1. A loom shuttle, comprising a body having bearings for the bobbin, and having a nose formed with a slot, and a tension lever pivoted to the body intermediate the bobbin and the nose and having a hooked end adapted to swing through the slot in the nose to facilitate the threading thereof.

2. A loom shuttle, comprising a body provided with bearings for receiving a bobbin, and with a nose having a slot, one wall of which is bent to form a loop; and a tension lever having a hooked end and pivoted on the body so that the hook may be passed through the slot, such lever having an arm adapted to operate the loom stop mechanism, said parts being arranged so that normally the thread passes from the bobbin over the

- loop, around the hook in the lever and outward from the slot, whereby the said arm of the lever is normally held in inactive position when the thread is under tension.
- 5 3. A loom shuttle, comprising a sheet metal body with upturned ends to constitute bearings for the bobbin, and an upturned nose transversely slotted to provide a rearwardly curved loop, a spring-tensioned 10 brake to engage the bobbin, a pivot rod therefor having a forwardly extending end, a tension lever having a hook and pivoted

on said body to allow the hook to swing forwardly through the slot to a point beyond the loop, and tension means connecting said lever with the end of the pivot rod.

In testimony whereof we have hereunto set our hands in the presence of two witnesses.

ROBERT FARNWORTH.
THOMAS TROUGHTON JACKSON.
